(57) **CLAIM**

The ornamental design for a spoiler for motor vehicle, as shown and described.

DESCRIPTION

FIG. 1 is a front side perspective view of a spoiler for motor vehicle;

FIG. 2 is a rear side perspective view thereof;

FIG. 3 is a front elevation view thereof;

FIG. 4 is a rear elevation view thereof;

FIG. 5 is a perspective view thereof from the left side;

FIG. 6 is a perspective view thereof from the right side;

FIG. 7 is a top plan view thereof; and,

FIG. 8 is a bottom plan view thereof.

The broken lines illustrate portions of the spoiler for motor vehicle that form no part of the claimed design.
